Primary Examiner — David G Muller*(74) Attorney, Agent, or Firm* — HONIGMAN LLP(57) **CLAIM**

The ornamental design for an external catheter stabilizer, as shown and described.

DESCRIPTION

FIG. 1 is an upper perspective view of an external catheter stabilizer in accordance with the present invention; FIG. 2 is a lower perspective view of the external catheter stabilizer of FIG. 1;

FIG. 3 is a top plan view of the external catheter stabilizer of FIG. 1;

FIG. 4 is a side view of the external catheter stabilizer of FIG. 1;

FIG. 5 is another side view of the external catheter stabilizer of FIG. 1; and,

FIG. 6 is a bottom plan view of the external catheter stabilizer of FIG. 1.
